UNITED STATES PATENT OFFICE.

LAWRENCE L. HANSEN, OF SPRINGFIELD, OHIO.

GOVERNOR.

Application filed September 11, 1922. Serial No. 587,634.

To all whom it may concern:

Be it known that I, LAWRENCE L. HANSEN, a citizen of the United States, residing at Springfield, in the county of Clark and 5 State of Ohio, have invented certain new and useful Improvements in Governors, of which the following is a specification, reference being had therein to the accompanying drawing.

My invention relates to governors and in particular to a governor controlling the intake of fuel.

It is the object of my invention to provide a governor which will control the 15 amount of fuel being admitted to the engine according to the speed of the engine and, upon the engine passing a predetermined speed, will cut down the supply of fuel.

It is another object of my invention to 20 provide such a governor which may be adjusted to suit the particular car.

It is a further object to provide a governor which will have the shock of its suddenly reaching its closed position suitably 25 absorbed to prevent injury to the mechanism and to also assist in dislodging the valve from its closed position in case it sticks.

It is an object to provide a governor 30 which will progressively cut down the supply of fuel as the speed increases in order to maintain an average speed.

In the accompanying drawings:—

Fig. 1 is a side elevation of my device with the cover broken away; and

35 Fig. 2 is a section taken vertically on the main axis of the governor showing the valve in open and closed position.

Referring to the drawings in detail, 1 is a supply pipe for fuel to a carburetor designated 2. The carburetor is attached to a special casting which consists of a delivery portion 3 connected with the carburetor by a nut 4. This portion 3 of the casing is provided with a passageway 5 which opens into a wide chamber or passageway 6 known as the governor valve chamber. In this chamber mounted on a shaft 7 is the valve member having two arms 8 and 9. Communicating with the upper portion of the chamber 45 is an exit passageway 10. This upper portion of the governor casing is attached to the manifold 11 by a nut 12.

Surrounding the governor casing is a housing 13 having a cover 14 mounted thereon and retained upon it by screws 15.

Within this casing and mounted upon the shaft 7 which projects through the wall of the governor casing is a lever 16 upon which is mounted a weight 17 at one end. The other portion of the lever is designated 18 and has on its outer end a contact head 19. This head is adapted to come in contact with a plate 20 mounted on a helical spring 21 which is supported in a bracket 22 on the outside of the governor casing. The pin 23 is provided as a stop to limit the downward movement of the arm 16.

As to the operation of the device, when the engine is started and the suction takes place through 5, 6, 10 and 11, the tendency 70 is to draw the valve members 8 and 9 to a position shown in dotted lines in Fig. 2 to shut off the supply of fuel. The greater the suction of the engine the greater the force exerted upon these parts.

75 In order to resist this action the lever composed of the part 16—18 is provided and the weight 17 is mounted on 16.

When the suction overcomes the effect of this weight and actually closes the valve, in 80 order to prevent any injury to the valve members, to prevent any rattling of the valve members against the inside of the governor casing and to absorb any shock incident to closing, I provide the spring 21 85 which comes in contact with the head 19 of 18 upon this closing taking place.

While I have shown and described certain features as constituting my invention, it will be understood that parts have been 90 shown for purposes of illustration only, and that I do not desire to be limited to such details, as obvious modifications will occur to a person skilled in the art.

Having thus fully described my invention, what I claim as new and desire to secure by Letters Patent, is:—

1. In a governor, a casing having fuel intake and exit passages, a valve member located therein having one portion larger than the other, the larger portion travelling in an expanded area in the casing, a lever on the outside of the casing connected to the valve member, a weight on said lever, a stop to limit the downward movement of said lever, 100 a second lever connected to the valve member to move therewith, a spring in the path of the second lever and engageable thereby upon the valve assuming a nearly closed position, 105

2. The combination with a valve casing consisting of a tubular member having an arcuate expansion on one side; of a butterfly valve mounted in said casing opposite the arcuate expansion, said valve having an eccentrically disposed pivot and the pivot being mounted eccentric to the expansion with

the wider portion of the valve moving in the expansion to engage the wall thereof at the extremity of its movement. 10

In testimony whereof, I affix my signature.

LAWRENCE L. HANSEN.
